UNITED STATES PATENT OFFICE.

FRANKLIN H. CONEY, OF CHICAGO, ILLINOIS.

COLUMN CAP FOR CONCRETE BUILDINGS.

Application filed December 18, 1922. Serial No. 607,594.

To all whom it may concern:

Be it known that I, FRANKLIN H. CONEY, a citizen of the United States of America, and a resident of Chicago, county of Cook, 5 and State of Illinois, have invented a new and useful Improvement in Column Caps for Concrete Buildings, of which the following is a specification.

This invention relates to buildings having reinforced concrete floors, and particularly to column caps for connecting the columns with the floors and reinforcing the structure at such point.

The object of the invention is to provide 15 a column cap of extreme simplicity and effectiveness for the intended work, and whose vertical dimensions are such that it may be contained between the upper and lower surfaces of the floor slab and be a 20 part of same.

The object of the invention is accomplished by the device shown in the accompanying drawing, wherein:

Figure 1 is a bottom plan view of a 25 column cap constructed according to this invention and showing in section a steel column incased in concrete.

Figure 2 is a sectional view taken on the line 2—2 of Figure 1, and includes a showing of the relation between the steel and 30 concrete parts of the structure.

It is well known that the maximum 35 stresses in a reinforced concrete floor and the most difficult to counteract, are those occurring in the floor adjacent to the columns. A number of plans have been proposed for properly reinforcing concrete structures at the points of connection of the columns and the floors. Some of the proposed arrangements involve unsightly enlargements of the 40 columns near the floor or require expensive and complicated forms, and others are more or less complicated in design, or unsatisfactory in not being of the required 45 strength or interfering with the pouring of the cement.

The construction shown in the drawings, so far as is known, overcomes all objections 50 to prior column caps, is of ample strength, is simple in design and inexpensive. This column cap or reinforcement is in the form of a frustum of a cone or a pyramid, or other dished arrangement having ring-shaped reinforcements at its outer and inner rims. The web connecting the inner and outer reinforced rings, is a laminated

plate having greater strength and thickness near the inner ring and tapering in thickness to the outer ring. The stresses produced in the cap due to the weight of the floor and 60 its load, results in the outer ring normally being under tension, and inner ring being under compression and the shear being resisted by the web between the rings.

As shown in the drawing, the column cap 65 consists of an inner collar-shaped compression member 1, the horizontal flange 2, of which, is riveted to the annular web member 3, built up from a plurality of ring-shaped plates 5, 6 and 7. The web member is of 70 dish form, i. e., inclined upwardly and outwardly from the compression ring 1 to the peripheral reinforcing tension rings 8 and 9. Rings 8 and 9 are riveted to the part 7 of the web member by the rivets 10, and 75 the parts 5, 6 and 7 of the web member are secured together by the rivets 11 and 12. The column cap through the compression member 1 rests upon the flanges 13 riveted to the steel part 14 of the column 15. The 80 floor rod reinforcements are indicated by the numeral 16, and these rod reinforcements may be arranged in any of the approved manners, such as according to the two or four-way systems.

Stirrups 17 at the periphery of the cap assist in resisting shear in the concrete, and also stirrups 18 depending from the cap inside of its periphery insure good adhesion 90 of the concrete to the cap.

From the foregoing it may be seen that the column cap tapers in thickness from the inner compression part 1 thereof, outwardly to the amply strengthened tension periphery of the cap, thus affording a reliable and 95 simple structure, not in any way requiring expensive forms for the concrete or interfering with the pouring of the concrete.

The specific design of the construction 100 herein shown and described, may be varied to suit different requirements as to strength and cost, the idea of the invention being mainly to provide a hollow metallic column cap conforming to the surface of an inverted frustum of a cone. The cap may be a single piece of metal of substantially uniform thickness, in which case, the metal near the outer edge, due to the greater circumference being in excess of that near the inner edge, will properly act in tension for circumferential stresses, as well as in compression for radial stresses. The metal near the inner

edge will take both radial and circumferential stresses. Likewise, the cap may also be made with inner and outer rings in different planes, as shown in the drawing, with the design of the connecting web varied to include open spaces with a series of connecting radial members between the spaces.

When a reinforced concrete column is used, holes will be provided in the cap for the reinforcing stem, and the open space in the center of the cap need then be large enough only for the filling of the column.

I claim:

1. A column cap comprising inner and outer reinforcing rings located in different parallel planes, and an annular web member connecting said rings.

2. A column cap comprising inner and outer reinforcing rings located in different parallel planes, and an annular web member connecting said rings, said web tapering in thickness from the inner ring toward the outer ring.

3. A column cap comprising inner and outer reinforcing rings located in different parallel planes, and an annular web member connecting said rings, said web tapering in thickness from the inner ring toward the outer ring, and comprising a plurality of plates secured together.

4. A concrete structure comprising a column on which is supported at the location of a floor, a floor reinforcement surrounding the column, said floor reinforcement comprising an outer tension ring and an inner compression ring, the inner compression ring being in a lower plane than the outer tension ring, and a web member inclined upwardly from the inner ring to the outer ring.

5. A concrete structure comprising a column on which is supported at the location of a floor, a floor reinforcement resting on said flange and surrounding the column, said floor reinforcement comprising an outer tension ring and an inner compression ring, the inner compression ring being in a lower plane than the outer tension ring, and a web member inclined upwardly from the inner ring to the outer ring, said web member tapering in thickness from the inner ring toward the outer ring.

6. A building comprising a floor supported on columns and a hollow metallic column cap connecting a column with the floor, said cap conforming to the surface of an inverted frustum of a cone.

Signed at Chicago this 17th day of November, 1922.

FRANKLIN H. CONEY.
